UNITED STATES PATENT OFFICE.

PAUL CHARPENTIER, OF PARIS, FRANCE, ASSIGNOR TO FORGES & ATELIERS DE CONSTRUCTIONS ELECTRIQUES DE JEUMONT, SOCIETE ANONYME, OF PARIS, FRANCE, A FRENCH JOINT-STOCK COMPANY.

ELECTRICAL CONTROL SYSTEM.

Application filed June 29, 1925, Serial No. 40,339, and in France August 2, 1924.

This invention relates to an electrical control system with master controller for the starting and regulation of electric traction motors or motor groups of high power and comparatively high voltage.

In equipments of this kind, the contacts governing the distribution circuits of the motors and of the auxiliary machines or apparatus assume the form of separate contactors with contact-pieces subjected to high pressure and energetic magnetic blow out.

These contactors, constructed preferably like switches, are operated in modern equipments by means of cam shafts actuated by any suitable driving means and are arranged to effect the usual successive combinations in the controlled circuit; in each position of the cam-shaft a series of cams of suitable shape is caused to actuate the lever 20 or levers of the contactors to be engaged.

This method of operation is open to objections except for simple equipments of comparatively low power; in the case of a large number of contactors traversed by currents of great intensity and high voltage, it necessitates cam-shafts of diameter, length and weight which are inadmissible.

There can however be employed in such a case several cam-shafts each operating a group of contactors; but this subdivision renders the operation of the plant more complicated. The actuation of contactors of large dimensions and their maintenance in position, by means of cams and rollers, entail heavy constructions and large operating forces; moreover the necessity of actuating masses of such magnitude and arresting them suddenly after small movements involves the danger of producing rapid wear and derangement of the parts.

These drawbacks are avoided in the system according to the present invention, in which instead of requiring a single member, the cam-shaft, to select the contactors for engagement and release to perform one or other of these operations, and to maintain the contactors in position, there is employed for each of these operations a separate member of suitable nature.

This system of preliminary selection further allows of selecting other apparatus in

the equipment at the time of the engagement or the release of a previously selected group and of performing these operations by means of a single controlling device. The actual 55 movement of this device, which is normally utilized for the selection, may likewise be employed for the operation in any suitable manner of certain apparatus of which the selection has been effected beforehand by 60 other devices.

The improved system therefore comprises essentially:

(1) A selector or combiner which selects either mechanically or electrically the contactors or other apparatus to be actuated.

(2) An operating device which effects the closing or opening of the contactors selected by the previous device or the operation of other apparatus already selected.

(3) A single controlling member which actuates successively the two previous devices, and of which two successive movements can be utilized for the operation of other apparatus selected in any suitable manner; the selector and the operating device for the apparatus can however be actuated each by a separate controlling member.

(4) Locking means which maintain the contactors or other apparatus in engaged 80 position after the controlling member has acted.

Upon the annexed drawings, to which reference is made in the subsequent description, the same letters and numerals designate the 85 same parts or elements.

Figure 1 represents by way of example a contactor with its operating devices, arranged in accordance with the invention, in the different stages of its movement.

Figure 2 is a perspective view of the details of the contactor operating mechanism shown in Figure 1.

Figure 3 is a diagram of an example of automatic operation of the selector or combiner and the operating member in accordance with the invention.

Figure 4 shows a form of construction of the main part of the selector or combiner.

Figure 5 illustrates a modification of the 100 operating means represented in Figure 3.

Figure 6 represents another device for

operating the selector or combiner and the operating member in accordance with the invention.

Figure 7 shows a form of operation especially intended for line circuit breakers.

Figure 8 is an arrangement for the operation of reversing switches, utilizing the first part of the movement of the controlling member.

Figure 9 illustrates the operation of a brake switch by means analogous to the preceding.

Figure 10 represents the arrangement of the control circuits with apparatus in accordance with the present invention.

Referring to Figures 1 and 2, the main lever 1 of the contactor is pivoted towards one end at 4 upon a stationary support 18 to which it is connected by a flexible lead 20 18₁; at its other end it carries contact piece 2, 2₁ designed to co-operate with a stationary contact piece 3 and an auxiliary contact finger 3₁.

The contact pieces 2, 3, 3₁ may be of any suitable type but are preferably arranged as indicated in the drawing.

The engaging and release movements of the contactor are obtained for example by means of an oscillating shaft 10, provided 20 with rollers 13, 14, mounted upon a part secured to the shaft 10 but insulated from the latter.

The combiner or selector is represented diagrammatically by one of its wheels such 35 as 15 carrying cams 16 of the requisite profile, acting upon a roller 21 mounted at the end of a lever 17 of suitable shape, pivoted at 19 upon the stationary support 18 and terminating in two branches carrying rollers 40 22 and 23 respectively.

These rollers 22 and 23 operate auxiliary levers 5 and 6 respectively, pivoted at 7 and 8 upon the main lever 1 and constantly pressed against the said rollers by springs 5₁ and 6₁.

The lever 6 carries at one end a hook 25 terminating in a branch 25₁ which is adapted to abut against the stud 25₂ secured on the wheel 15.

The other end of the lever 6 carries pivoted at 6₄ a finger 6₂ having a ramp 29 and a lug 9. The two integral members 9 and 6₂ are constantly urged towards the position of rest (Figure 1) by a spring 6₃; their function will be explained later.

When the wheel 15 of the combiner turns through the desired angle, one of its cams 16 is made to raise the roller 21; the lever 17 thus actuated pivots around the axis 19, and its roller 22 pushes back the lever 5, which rocks about the pivot 7 and brings a ramp 24 into the path of the roller 13 on the oscillating shaft 10.

If then this shaft 10 is turned in the clock-

wise direction, the roller 13 engages under 65 the ramp 24 and causes the lifting of the auxiliary lever 5 which continues its rocking movement until it abuts against a stop 5₂; the main lever 1 is then rigidly operated together with the movable contact piece 2, 2₁ 70 which comes to press upon the stationary contact piece 3, 3₁. Rubbing action and firm pressure between the contacts 2 and 3, 3₁ will be ensured by springs 2₂ and 3₂ controlling the pivoted contacts 2, 3₁. The 75 circuit controlled is thus closed.

At the same time, the hook 25 of the other auxiliary lever 6, receiving the same movement as the lever 1, engages upon a ledge 26 on the support 18 and maintains the contactor in closed position, with the roller 21 pushed back by a cam such as 16; the shaft 10 however is returned to its position of rest (Figure 1).

If the wheel 15 then continues to rotate 85 and the cam 16 moves away from the roller 21, a spring 27 arranged between the lever 17 and the support 18 pushes back the lever 17 towards the left of the figure, the branch 20 of this lever then pressing its roller 23 90 against the lug integral with the finger 6₂. The engagement of the roller 23 with the lug 9 turns the finger 6₂ around the pivot 6₄ until the back of the lug strikes at 30 against the main portion of the lever 6; the finger 6₂ then has its ramp 29 placed in the path of the roller 14 upon the shaft 10.

If the shaft 10 is again oscillated in the clockwise direction, its roller 14 engages the ramp 29 and pushes back the finger 6₂ the 100 movement of which is limited by a stop 30, and then rocks the lever 6 around the pivot 8 by means of a finger 6₂ and the lug 9. A stop 65 limits the rocking movement of the lever 6 in this direction. The hook 25 105 now slips off its ledge 26, and the main lever 1 of the contactor being freed turns around the pivot 4, separating the movable contact pieces 2, 2₁ from the stationary contact pieces 3, 3₁ so as to break the circuit. As soon as 110 the rotation of the shaft 10 and the consequent displacement of the roller 14 release the lever 6, all the parts of the system resume their position of rest (Figure 1) in readiness for further operations.

The actual operation of the contactors, after preliminary selection, as described above, is given merely as an example and may evidently be obtained in many other ways.

An important feature of the invention consists in producing the release of all the contactors by the return of the zero of the selector device. For this purpose the arm 25₁ of the hook 6 is so shaped that it is only 125 struck by the stud 25₂ carried by the wheel 15 of the selector during the return movement of the latter to zero.

The stud 25₂ then causes the arm 25₁ to move back, the hook 25 being actuated to move off its ledge 26, and the lever 6 resuming its position of rest (Figure 1), while the contact pieces 2 and 3 open in the manner previously explained.

The arrangement represented in Figure 1 comprises a pawl 48, pivoted at one end upon a stationary axis 49 and pivotally attached at its centre to the movable core of an electromagnet DV; the other end of the pawl is adapted to engage in a notched wheel 50 keyed upon the shaft of the selector or combiner. When this electromagnet DV is energized, its movable core is attracted, operating the pawl 48, which rocks around the pivot 49 and engages over one of the teeth of the wheel 50, but as soon as the excitation ceases, a spring 51 arranged between the pawl 48 and the stationary frame or support of the magnet DV releases the pawl from the notch in the wheel 50.

The equipment control must comprise suitable driving means for producing first the rotation of the mechanical selector or combiner, then the operation of the oscillating shaft or other device for engaging and releasing the contactors picked out by the selector.

Depending upon whether the working is to be automatic or not, the operation of the driving means may continue automatically after once being started, or may require the intervention of circuits or contacts established by the master controller in each working position.

The operation of the contactors in an automatic equipment comprising the system described above, may be carried out for example by means of an electromagnet b (see Figure 3), having one extremity of its winding earthed by a lead a' and the other connected to a lead a, the supply of current to the latter being regulated by a master-switch or drum-type controller of any suitable type. This magnet b may be energized intermittently, for example by means of a bascule or see-saw contact b₄, of known type.

The magnet b carries pivoted to its movable core b₁ a pawl b₂ which engages upon the teeth of a ratchet wheel b₃ so as to advance the latter through a given angle at each stroke of the said core b₁. This wheel b₃ is keyed to the extremity of a shaft g carrying the cam-wheels such as 15 and 15₁ of the combiner or selector.

Moreover the movable core b₁ is provided with a contact piece c adapted to close the supply circuit d to a second electromagnet e each time that the core b₁ reaches the end of its stroke. To the core e₁ of the magnet e there is pivotally attached a crank device e₂ secured to one end of the oscillating shaft 10, carrying the rollers such as 13, 14 and 13₁,

14₁ operating the levers 1 and 1₁ of the contactors, which are not shown in Figure 4.

The movement of the core e₁ produces the oscillation of the shaft 10 by means of the crank e₂.

On the other hand, upon the lead a' there is mounted a contact f₁ operated by an accelerating relay or current limiter f controlling the rotation of the shaft g and therefore the successive combinations of the contactors, the other elements of the equipment being arranged in the ordinary manner.

It will readily be understood, in view of the explanations given above, that the operations effected by the combiner or selector require only very small forces, since they consist merely in altering the position of one or other of the levers such as 5 and 6 or in maintaining them at rest; the parts can therefore be of small size and strength.

If the equipment involves a large number of combinations, the diameters of the wheels such as 15 and 15₁ can nevertheless be kept small by arranging the cams such as 16 along one or more helices instead of around a circle.

The wheels such as 15 and 15₁ may then have the profile of a square-threaded screw provided with cams such as l m (Figure 4), the shaft g terminating in a screw j revolving in a bearing k forming a nut of the same pitch as the wheel 15; consequently at each revolution of the shaft g the cams such as l of one thread h for example will move away laterally giving place to the cams such as m of the adjacent thread i. This method of construction easily allows the provision of selectors giving more than forty positions, with a cam wheel of not more than six-inch diameter.

In certain cases, especially for brake-operation, it may be necessary after having returned the combiners or selectors to the position of rest, to make them rotate afresh while actuating contactors adapted to produce combinations different from those previously established or contactors not previously utilized.

For this purpose, the shaft g may be displaced in the direction of its axis by means of an electromagnet such as n the exciting circuit of which will be closed by a supplementary contact, for example as soon as the driver turns his switch handle to the first braking position; such an arrangement allows the rapid establishment of the combinations required for brake-application.

The displacement mentioned may be of any suitable kind; for example the bearing-nut k may be fast with the core p of the magnet n which carries it along in its stroke, the nut k remaining held against rotation by a stop or slide q in the case of helicoidal braking cams but being drawn out of en-

gagement with such stop to allow simple rotation in the case of plane braking cams (Figure 4). As soon as the magnet n is de-energized, the shaft g slides back into place.

In the braking position, another cam wheel r , fast with the wheel 15 for example, and carrying suitable cams, comes into place under the rollers such as 21 of levers similar to the levers 17. It will be understood that a wheel r with helicoidal cams might also be employed for brake control to function in the same way as the wheel 15.

In order to save time in the application of the brakes, there is arranged between the thread h of this wheel 15 and the cam wheel r , a ramp s which slides along beneath the rollers such as 21 of the contactor levers 17 which are to be actuated in the first braking position.

For a step-by-step advance and a sudden return to zero of the selector or combiner, there may likewise be utilized the arrangement comprising a toothed wheel b' , with pawl b'' (see Figure 5) as well as a toothed pinion t with toothed sector u , respectively operated by electromagnets b' b'' .

The electromagnet b' advancing the toothed wheel b' , keyed upon the shaft g arranged as in Figures 3 and 4 will at the end of its stroke close the contact c' arranged in the supply circuit d' of the magnet e' operating the oscillating shaft 10 in the manner above described with reference to Figure 3.

The invention may further be applied to any other system of master-control operation by electromagnetic means, auxiliary motor, compressed air cylinder and piston, or the like, for effecting successively the step-by-step advance or return of the selector or combiner and the simultaneous oscillations of the shaft 10. The return of the combiner to zero may likewise be effected by means of a suitable spring acting upon the shaft of the combiner, in the manner already known for certain types of controller.

After having returned the combiner to its zero position, it may however be necessary to effect the opening of certain contactors still in engagement, and therefore to produce a supplementary oscillation of the shaft 10 operating these contactors, without actuating the driving means of the combiner which would take up its first working position.

For this purpose, the toothed sector u may be connected to the electromagnet b by means of a pivotal link v and crank w , the latter carrying a contact piece u_1 which at the end of its stroke (i. e. after the return to zero of the combiner) will close an auxiliary circuit ω supplying the electromagnet e' which operates the shaft 10. This magnet e' when energized will oscillate the shaft

10, which will produce the release of the contactors still closed, since in the zero position the combiner picks up the whole of the contactors for opening the circuits, or at least those which have to be released in the off position of the switch or controller.

The system represented in Figure 5 is given merely by way of example and comprises three operating electromagnets, but the invention might also be carried out with the arrangement described hereafter with reference to Figure 6; the latter requires only two electromagnets, one of them being a selecting magnet of low power.

Upon the oscillating shaft 10 (Figure 6), there is mounted a loose sleeve F operated in any convenient manner by an electromagnet G or by any other means of sufficient power to engage three or four contactors at once.

The said magnet G is energized under the control of the master switch, at each step in its working, or else intermittently under the action of a bascule contact of known type.

A crank A keyed upon the loose sleeve F is attached to a connecting rod B terminating in a claw B_1 of suitable shape, which in the position of rest bears upon a stud C fixed to a whistle or rocking bar K .

Another link and crank group MN is attached on the opposite side to the group AB , but in this case directly, to the oscillating shaft 10.

The bar K is pivotally connected at its two extremities respectively to the link M at the end L and at the other end to the feed pawl D of the toothed wheel b'' , keyed upon the shaft g of the combiner.

The electromagnet G when energized produces the rotation of the sleeve F in clockwise direction, the shaft 10 remaining stationary; the crank A and link B thus operate rock the bar K around the pivot L by means of the stud C and the claw B_1 . In this operation the rocking bar K tends to lower the link M and crank N , but such movement is prevented by the resistance encountered by the shaft 10 in oscillating to close the contactors, a resistance being afforded by a suitable spring P for example.

The bar K lowers the pawl D which engages over one of the teeth of the ratchet wheel b'' , and advances the latter by one step, tensioning a spring P_1 and then striking against a stop Q ; the force of the crank A is then transmitted through the rocking bar K to the link M and to the crank N , the shaft 10 therefore oscillating and engaging the contactors selected by the combiner which will already have advanced by one step.

If the excitation of the magnet G ceases at this moment, its core resumes its position

of rest under the action of the springs P and P₁ and all the parts of the system will be in readiness to perform further movements, such as that described above, as soon as the magnet G becomes energized again.

In order to produce the return of the combiner to zero, the circuit G₁ of the magnet G is opened while the circuit S of a selection magnet R is supplied automatically, either by the return of the master switch to zero, or by auxiliary contacts on the line switches or circuit breakers, according to the known methods.

The movable core R₁ of the magnet R is connected to the link B by a jointed rod R₂.

This magnet R when energized pushes the said link B towards the left, its claw B₁ being thereby freed from the stud C and the link bringing a ramp B₂ into the path of another stud T carried by a lever U pivoted at one end at L upon the rocking bar K and link M, and at the other end at U₁ to the end of the link V operating the sector t' meshing with the pinion u' serving to re-

turn the combiner to zero.

The movable core R₁ carries a contact piece R₃ which at the end of its stroke recloses the supply circuit G₁ of the magnet G. The sleeve F thus actuated oscillates the crank A, and the ramp B₂ of the link B pressing upon the stud T draws down the lever U and link V until their pivotal connection U₁ encounters a stop X₁, the joint L common to the members M, K and U being so far held stationary by the spring P. The combiner is thus returned to zero by t' and u'. The link B continuing its movement, the lever U pivots around the point U₁ and then falls so as to tension the spring P while the attached link M produces the part-rotation of the crank N so as to oscillate the shaft 10. The rocking bar K will likewise fall at the same time as the joint L, but without actuating the pawl D, merely turning around the joint between K and D.

The previously described mechanical means for operating the contactors may be utilized in place of the electric combiner, with electromagnetic contactors, employed in known control systems, all the other features of the control system remaining unaltered as regards the step by step operation, the automatic working and so on.

It may be remarked that the successive engagements and releases of the contactors being determined in a positive manner, in the improved device, by the position and the shape of the selector cams, there is no possibility of error in the operation of the said contactors and it is unnecessary to provide any interlocking means for preventing their accidental opening or closing; the improved device therefore presents a great advantage over the ordinary cam-controllers in which the contactors may stick in closed position

(due to overheating or burning) without the rotation of the cam-shaft being arrested, thereby producing short-circuits in the traction circuit.

In the present invention, the releasing forces are in general sufficient to open contacts which have become slightly stuck together, but if these contacts should resist the action of the oscillating shaft, the latter would no longer be able to open or to close the contactors at the subsequent working positions, because its roller 14 would be held fast upon the ramp 29. This feature provides a means for placing the traction circuit out of operation, by cutting the control circuit.

For this purpose one of the members acting upon the oscillating shaft 10, for example the link B, is formed in two parts; the lower part carries a shank Z adapted to slide in the interior of the upper part, bearing upon a suitable spring Z₁ surrounding it and tending to bring the two parts together.

If the shaft 10 and therefore the rocking bar K and claw B₁ of the link B are blocked due to the sticking of the contacts on any of the contactors, the loose sleeve F turns alone under the action of the magnet G and actuates the lower part of the link B which in descending opens a contact J; the latter is arranged to open the line contactors, for example by interrupting their current supply, so that the whole operation is held up.

In the case of an automatic equipment with operating electromagnet acting as a trembler, the core of the magnet will be arrested in its movement, due to the blocking of the shaft 10 by the stuck contacts, and the whole operation is again held up, without any special safety devices.

Figure 7 represents an operating mechanism for circuit breakers or line switches designed to break traction circuits in case of overload or drop of line voltage by utilizing:—

For the engagement, the oscillating shaft of the running contactors, thus suppressing the means usually necessary for the operation of the controlled apparatus.

For the release, an electromagnet operated by drop of voltage to a given minimum value.

The oscillating shaft 10, Figure 7, can engage by either one of its rollers, 13 for example, the ramp 33 of the auxiliary lever 35, fixed upon the main lever 37; the latter is pivoted to the support 38 and carries the contact piece 39 of the circuit breaker represented by the contacts 39—40.

On the other hand, one end of the auxiliary lever 35 is connected by a rod 41, the purpose of which will be indicated hereafter, to the opposite end of the auxiliary lever 36, likewise pivoted upon the main

lever 37. The lever 36 is pivotally attached at its other end to the movable core of an electromagnet 42 mounted upon the support 38 and energized by means of a lead 43 connected to the traction circuit, either directly or through suitable resistances. The magnet 42 thus operates as a voltage relay.

If the magnet 42 is energized, the lever 35, pushed forward by the lever 36 and the rod 41, tilts in the counter clockwise direction.

When the shaft 10 oscillates in the clockwise direction, its roller 13 engages under the ramp 33 on the auxiliary lever 35 and raises the latter; the main lever 37 is thereby operated to close the contacts of the circuit breaker. The lever 36 at the same moment brings its hook 44 in front of a ledge 45 upon the support 38.

If the electromagnet 42 remains energized, its movable core being attracted compresses a spring 46 arranged between the lever 36 and the support 38, and the hook 44 engages upon the ledge 45 being pressed forward by a flexible plate 47; the circuit breaker or isolating switch will remain engaged so long as the electromagnet 42 remains energized, while the oscillating shaft 10 resumes its position of rest.

The energization of the magnet 42 becomes insufficient as soon as the line voltage falls by a predetermined amount; the spring 46 then pushes back the lever 36, the hook 44 of which becomes disengaged from the ledge 45, and all parts resume their position of rest shown in Figure 7. The circuit-breaker opens and the system is placed in condition for fresh operations which are carried out successively as indicated above.

In order to obtain the opening of the circuit breakers under the action of the overload relay, it is only necessary to provide the latter with a contact RS₃ (Figure 7) which will cut the lead 43 as soon as the overload relay operates.

If the equipment comprises brake action, for example by motors acting as generators closed upon resistances, the circuit having to remain open during this mode of running, the auxiliary lever 35 (Figure 7) may be operated for example by one of the cams of the combiner and a lever such as 17 (Figure 1), for the engagement of the circuit breakers in the power-running positions. Since for the preparation of the brake operation, the combiner shaft is first of all displaced in the direction of its axis, the contactor-engagement cam moves away from the roller such as 21, and the circuit breakers will not be actuated by the oscillating shaft as it brings the brake into action.

In addition to this feature of the operation of the circuit breakers in the two modes

of running, the invention possesses the characteristic of the operation of the reversing switch not by the oscillating shaft but by the loose sleeve F (Figure 6). In this manner the line circuit breakers can never be closed before the reversing switch has been actuated, and conversely the reversing switch cannot be operated unless the circuit breakers are in open position, since the rotation of the sleeve F necessarily precedes that of the oscillating shaft 10.

In brake operation, there may likewise be employed a brake switch actuated together with the sleeve F before the oscillating shaft 10 engages the contactors for the first braking position.

Figure 8 represents by way of example, a method of carrying out the control of the reversing switch based upon this principle.

In this figure the loose sleeve F actuated by the single operating means controlling the equipment acts upon a system of links and rocking bar analogous to that of Figure 6. The free end of the rocking bar K₁ engages one or other of the links 51₁ and 52, which each operate the shaft 53 of the reversing switch in a different direction of rotation.

Discrimination of the direction of rotation of the reversing switch may be effected by the engagement of the hooked end of one or other of the links 51₁, 52, upon the stud 54 on the rocking bar K₁, according as one or other link is drawn towards the rocking bar by the oscillation of an intermediate shaft 55 in one direction or the other. This shaft 55 carries two levers 56 and 57 which act through springs 58 and 59 upon the links 51₁ and 52 respectively. Two other levers 60 and 61, fast to the shaft 55 are operated respectively by two small electromagnets 62 and 63, energized by the usual two control leads to the reversing switch. It can readily be seen that according as one or other of these magnets is energized, the movement of the rocking bar K₁ will actuate one or other of the links 51₁ or 52. This movement being effected, the rocking bar K₁ will abut against a support 64 and the sleeve F will then actuate the oscillating shaft 10, as has been explained above. In the subsequent oscillations of the rocking bar, the latter will have no further action upon the link 51₁ or 52 which it has operated, and the reversing switch will be maintained in place. If at a suitable moment, the other electromagnet 62 or 63 is energized, the reversing switch rocks in the opposite direction.

Figure 9 represents an analogous method of operation for the brake switch.

In this figure, the rocking bar K₂ actuates the link 65 when the latter has been hooked upon the stud 66 on the rocking bar under the action of the spring 67 tensioned by the

attraction of the core of the electromagnet 68. The movement of the rocking bar thus produces the rotation of the shaft 70 of the brake switch, tensioning a spring 71 tending 5 to return the shaft 70 to its position of rest. At the same time as the rocking bar comes to rest upon the stop 69, the shaft 70 is held fast by a pawl 72 which will be freed by a rod 73 fast to the core of the magnet 68, 10 as soon as the latter is de-energized. The shaft 70 will then return to its position of rest and the link 65 will be freed from the stud 66 under the action of the spring 74, the spring 67 being relaxed at the same 15 moment.

The succession of the operations of selection and actuation of the apparatus is ensured by the use of auxiliary contacts mounted upon the shafts such as 53, 55, 70, 20 or upon any other moving part in the system. These contacts arranged according to known methods of which however a very advantageous application is made in this case, have for their object firstly to set the 25 driving means of the control system in movement only after selection of the apparatus to be actuated and further to interrupt the current supply to the selecting devices or driving means when they have performed 30 their function.

Thus for example, the contacts 201, 202 and 203, 204 (Figure 10) are controlled by segments 210, 211 upon the drum CV, mounted upon the shaft of the reversing 35 switch. The contacts 201, 202 are closed by 210 if the reversing switch is in the forward travel position; 203, 204 will be closed by 211 if the reversing switch is in the reverse travel direction. The contacts 205, 206, 207 40 are controlled by segments 208, 209 on the drum CV₁, mounted upon the selection shaft 53 (Figure 8) or are fast to the movable cores of the selection magnets 62, 63. The contacts 205, 206 or 206, 207, will be closed 45 by their respective segments when one of the selection magnets 62, 63, becomes energized.

In Figure 9 there are likewise represented the selection devices necessary for obtaining 50 by a single movement the position of the combiner which selects the contactors corresponding to the emergency braking position, with the motors short-circuited.

In this figure, the rocking bar K₂ or a 55 member fast to the latter or to the sleeve F, actuates a link 75 which carries a hook 80 and which is drawn towards the shaft g of the combiner so as to engage over a tooth 76 carried by a sleeve upon this shaft, when 60 the magnet 77 is energized through a special lead from the master switch so as to tension the spring 78 attached to the link 75. The tooth 76 being at a smaller radius from the shaft g than that of the toothed wheel 65 b''₃ (Figure 6), the stroke of the rocking

bar K₂ will cause the shaft g to perform a rotation corresponding to several steps of the combiner, and to attain by a single movement the short-circuit braking position. When the excitation of the magnet 70 77 is interrupted, the spring 79 returns the link 75 backwards.

The above examples show how the invention allows of actuating successively several apparatus in the equipment by the member 75 operating the shaft g of the selector (Figures 3, 5, 6), and by the means driving the oscillating shaft 10 (Figures 3, 5, 6), in cases where this succession of operations has particular interest from the point of 80 view of safety in working.

But it may also happen that it is required to actuate various apparatus at the end of one of the diverse connections (series-parallel and the like), as is the case for 85 example for a field shunting switch, without there being any need to observe a succession of the operations of these apparatus with other parts. In this case, the invention will allow of effecting these movements simply 90 with the oscillating shaft such as 10, which will be engaged with the shaft of the apparatus to be controlled, by means of systems of electromagnets and selection links analogous to those shown in Figures 9 and 10. 95 The movement of these electromagnets, in determining the engagement with the shaft 10 and not with the sleeve F, as in the aforementioned figures, will produce a current supply to the means operating the shaft 10 100 and provide a supplementary working position. When this position has been attained, the supply to the driving means can be suppressed by the movement of the apparatus operated and matters can be restored to the 105 normal state after cessation of the employment of this apparatus by the simple return movement of the selection electromagnet to the position of rest.

Figure 10 represents diagrammatically an 110 arrangement of the circuits and apparatus intended to provide an automatic control of an equipment comprising contactors with the arrangements described above with reference to Figures 1 to 8 of the drawings. 115

Such an equipment may comprise a certain number of contactors serving to effect in a given order the diverse combinations and connections of traction circuits (not represented in the drawing), as well as the 120 operations necessary for their protection.

Control is provided for rheostat starting and resistance braking with a further braking step arranged as a short-circuit for the traction motors.

In this Figure 10,

M is the master switch drum or cylinder.

V is the drum or cylinder controlling the reversing switch.

CV and CV₁ are auxiliary contacts on the 130

reversing switch; CV_1 is mounted for example upon shaft 55 of Figure 9, and CV is mounted upon shaft 53 of the reversing switch.

5 EA is the electromagnet controlling the operation of the system.

SC is a segment provided for overload working.

10 SL are the auxiliary contacts actuated by the shaft of the combiner or selector.

RL₁, RL₂ are the auxiliary contacts on the line circuit breakers.

15 RL₁, RL₂, and RL₃ are the auxiliary contacts on the overload relay.

RA is the auxiliary contact of the accelerating relay.

BP₁ is the auxiliary contact on the overload working relay.

20 BA₁ is a contact operated by an auxiliary relay.

SF is the electromagnet for selecting the brake action (corresponding to 68 in Figure 9).

25 RP represents the electromagnet n for sliding the shaft of the combiner (Figure 4).

30 FU is the electromagnet causing the rotation of the combiner at a single movement to the emergency braking position (corresponding to 77 in Figure 9).

V₁ V₂ indicate the selection magnets for the direction of travel (corresponding to 62 and 63 in Figure 8).

35 The different apparatus are indicated only by their contacts or the windings of their operating electromagnets.

40 The master switch or controller comprises three handles, namely: a main handle controlling the drum or cylinder M, a reversing handle controlling the cylinder V, and an overload handle controlling the segment SC.

45 The main handle, in moving over the zero position in the return direction passes into the braking positions but there might equally well be employed a special handle for brake operation.

50 The handle of the cylinder M is interlocked mechanically with the handle of the cylinder V, by any suitable device not represented.

55 It has been assumed that the master controller is constituted by a series of segments and corresponding fingers, but it is to be understood that this apparatus might be constructed in any suitable manner on condition that the current supply to the controlled circuit is controlled in the manner hereafter indicated.

60 The nature and the function of the various apparatus in the system will be made clear in the course of the description; these apparatus are in general illustrated in their position of rest, but their respective positions in the different phases of the operation will be stated hereafter.

In order to set the control system in operation, the master switch being at the zero or off position, the handle of the cylinder V controlling the reversing switch is set to the position AV or AR according to the direction desired; the handle of the cylinder M of the master switch is then pushed to the first working step, whereupon electrically connected segments 106, 107, 108 on the said cylinder M come respectively into engagement with fingers 109, 105 and 110, 109 being connected to the lead 139 for the control supply, 105 being connected to the finger 104 by the lead 111, and 110 leading to the conductor 116 in the control circuit.

70 One of the direction-selecting windings V₁ or V₂ of the reversing switch (Figure 8) is then energized, the circuit being traced through the lead 139, finger 109, segments 106 and 107, finger 105, lead 111, finger 104 of the cylinder V, and either by contact stud 100, finger 103, lead 112, and the lower auxiliary contacts of CV₁, for the winding V₂ for the forward direction of travel AV, or else by contact stud 101, finger 102, lead 113, and the upper auxiliary contacts of CV₁ for the winding V₁ for the reverse direction of travel AR.

75 The windings V₁ and V₂ are connected to earth in parallel through the auxiliary contact RL₁ of the line circuit breakers; it is indispensable that this last contact be closed and the circuit-breakers open, before either of the windings V₁ V₂ can be energized.

80 As soon as the selection represented in Figure 9 has been effected, one of the auxiliary contacts of CV₁ closes, supplying current to the main lead 114 of the control circuit.

85 As soon as the reversing switch has functioned, the auxiliary contacts of CV which have been brought into use open to break the circuit of the winding V₁ or V₂ previously energized.

90 In known systems, the conductor corresponding to 114 supplies the electromagnets which operate the line circuit-breakers directly or through an intermediary, but in the system according to the present invention, the conductor 114 is connected to the fingers 119 and 118 of the selector bridged by a contact 115 in the zero position of the said selector, then to the auxiliary contact RS₁ of the overload relay, and finally to the electromagnet EA which regulates the working of the mechanical selector and of the oscillating shaft in the manner already set forth. The magnet EA is earthed through a bascule contact 117 and the contact RA of the accelerating relay. The bascule contact 117 carried by the core of the magnet EA may be of known type producing the trembler-like operation of the electromagnet EA.

95 The magnet EA is energized through the

lead 114 only while the combiner and the overload relay are both in the position of rest, with their respective auxiliary contacts 119, 115, 118 and RS₁ closed.

5 If these conditions are fulfilled, the magnet EA will be energized in the position I of the master switch, and its core will vibrate under the control of the bascule contact 117, producing if required the movement 10 of the reversing switch by the rocking bar K₁ (Figure 8) and the advance of the selector through one step (from position O to position O₁) followed by the engagement of the line contactors (not shown in the drawing) by the oscillating shaft 10. The contact 115 has thus been moved away from the fingers 118 and 119 and has cut the above described supply circuit of the magnet EA, while the segments 122 and 128 of the selector or combiner come respectively into engagement with the fingers 120, 121 and 129, 130, the function of which will be explained later.

From this moment onwards, the electromagnet EA is energized by another circuit comprising the finger 110, segment 108, lead 116 which includes the auxiliary contact RL₂ of the line circuit-breakers (now closed), and the selector fingers 120 and 121 bridged 30 by segment 122 except in the zero position of this apparatus.

The magnet EA now performs a fresh oscillation under the control of its bascule contact 117, thereby advancing the selector 35 by another step; the selector then assumes the position I and effects the closure of the contactors selected by the latter by means of the devices already described; moreover a stud 124 and a segment 127 on the selector 40 come respectively into engagement with the fingers 123, 125, and 131, 132.

The traction circuit combinations thus effected correspond for example to series 45 operation of the traction motors with all the resistances in circuit.

If it is desired that this method of operation be continued until a further action on the part of the driver the bascule contact 117 can be short-circuited by the lead 126 extending from the lead 116 after the magnet EA to the selector fingers 123, 125, now bridged by the stud 124. In the circuit of this lead 126 there are arranged the contacts BA₁ of the auxiliary relay.

55 The magnet EA will thus be energized in a continuous manner and its core upon reaching the end of its stroke will be held stationary, together with the selector and the oscillating shaft; the series connection of the traction motors with all the resistances in circuit will continue so long as the master controller occupies the position I.

When the driver pushes the master handle 60 from the position I to the position II, a segment 133 electrically connected to the afore-

mentioned segments 106, 107, 108, will come into engagement with a finger 135 arranged upon a conductor 133, connected to the selector finger 132 then bridged to the corresponding finger 131 by the segment 127.

70

The said finger 131 is connected to the lead 138 supplying the auxiliary relay of which the contact BA₁ is normally closed; when energized this relay opens its contact BA₁ and suppresses the short-circuit across the bascule contact 117. Under the action of the latter, the magnet EA again oscillates automatically causing the step by step advance of the selector and the to and fro movement of the oscillating shaft; these 80 apparatus effect the required successive combinations in the control circuit. This automatic operation takes place under the control of the accelerating relay, the contact RA of which interrupts the lead 116 as soon as 85 the traction current exceeds a given value.

85

In order to arrest the automatic operation of the system at any desired position, full series for example, it is only necessary to short-circuit the bascule contact 117 once 90 more. For this purpose the segment 127 of the selector moves off the fingers 131, 132 when the selector passes to the last series position, and breaks the excitation of the auxiliary relay; its contact BA₁ thereupon 95 closes while another stud 137, identical with the aforementioned stud 124, bridges the fingers 123, 125.

95

In order to avoid premature intervention of the accelerating relay as well as the opening of its auxiliary contact RA and the stoppage of the electromagnet EA before its core has reached the end of the stroke, a contact 140 operated by this core and included in a lead 123, forming a shunt to the lead 116, will short-circuit the said contact RA and its winding, as soon as the core of the magnet EA moves; the contact 140 will open again only after this core has resumed its position of rest.

100

When the driver pushes his master controller handle from the position II to the position III, the stud 134 on the drum M electrically connected to the aforesaid segments 106, 107, 108 and 133, will place it- 115 self beneath a finger 136 connected to the finger 143 of the cylinder V by the lead 142; in this manner, during forward travel only, the finger 143 will be bridged by a stud 145 to a finger 144 arranged in a lead 141 extending to the selector finger 146 bridged to the finger 147, mounted upon the lead 138, by a segment 148, these connections being established in the last of the series working steps, for example. The automatic oscillation of the electromagnet EA can thus be resumed in forward travel, to provide the successive steps of operation with parallel connected motors, the auxiliary relay being energized by lead 142, finger 143, stud 120 125 130

145, finger 144, lead 141, finger 146, segment 148, finger 147 and lead 138. The lead 126 is then interrupted at the contact BA₁.

From the aforementioned lead 116 there is arranged a branch circuit 116₁ supplying the auxiliary electromagnet DV (Figure 1); in this circuit 116₁ are included the auxiliary contacts RL₃ of the line circuit breakers and RS₂ of the overload relay as well as a special contact 154 (hereafter described) controlled by the electromagnet EA, and finally the earthed finger 130 bridged to the finger 129 by the segment 128 on the selector, as soon as this latter leaves the zero position. In order that the magnet DV shall be energized, it is necessary on the one hand that the contacts RL₃ and RS₂ be closed (that is that the line circuit-breakers be likewise closed and the overload relays in position of rest) and on the other hand that the magnet EA perform a predetermined movement, the selector occupying any position other than the zero position.

The supply to the electromagnet DV is regulated by the contact 154 operated by the movable core of the main electromagnet EA by means of any suitable device.

The movement of the magnet EA actuating the contact 154 will result in opening the latter and breaking the excitation of the magnet DV; the wheel 50 is unlocked as well as the selector which can therefore advance one step.

But the contact 154 recloses as soon as the electromagnet EA has performed a certain length of stroke, and the magnet DV being energized draws the pawl 48 into the next notch in the wheel 50 as soon as it offers itself. It can easily be seen from the foregoing explanation that the positions of the selector will thus be rigorously controlled and maintained apart from the direct action of the magnet EA.

The opening of the line circuit breakers will result in breaking the circuit of the electromagnet DV at RL₃ (see Figure 10): the pawl 48 will be moved away from the notches of the wheel 50 by the spring 51 and the selector will be able to return to the zero position under the action of a suitable spring or electromagnet device.

Overload operation may take place in spite of the intervention of the accelerating relay by the operation of the segment SC which serves to bridge a finger 149 branched from the lead 111, to a finger 150 connected to the supply lead 151 of the overload operation relay winding, the other extremity of which is earthed. The said winding when energized causes the closure of its auxiliary contact BP₁ included in a branch 126₁ of the lead 116, and short-circuits the bascule contact 117 and the accelerating relay in the manner indicated above.

Consequently the magnet EA will be held stationary at the end of its stroke, in spite of the opening of the auxiliary contact RA₁ of the accelerating relay, this condition subsisting so long as the segment SC bridges the contact fingers 149, 150 under the action of the overload operation handle.

It is easy to see from the foregoing that all desired combinations of the traction circuit can be obtained by means of parts or elements such as those utilized for the series parallel operation of the traction motors described above.

Protection of the traction circuit is ensured in the customary manner by overload and voltage relays, as well as the suppression of the supply to the control circuit when the handle of the master controller drum M is returned to zero.

However the invention is further characterized by the fact that the voltage relay is constituted by the minimum voltage electromagnet 42 (see Figure 7) which in the manner hereafter described causes the release of the line circuit breakers as soon as its excitation ceases.

This magnet 42 (Figures 7 and 10) has one extremity of its winding earthed, the other extremity being connected to a circuit comprising the lead 153 (Figure 10), branching from the lead 116, and an auxiliary contact RS₂ of the overload relay, in such a manner that the said circuit will be interrupted and the line circuit-breakers will release:

(1) If the overload relay operates, by the opening of the auxiliary contact RS₂.

(2) If the voltage of the supply line falls by a predetermined amount.

(3) If the cylinder M of the master controller is returned to zero.

The line circuit-breakers must not be able to be engaged if the voltage fails: for this reason the rod 41 (Figure 7), attached to the opposite ends of the levers 35 and 36, will be moved towards the right by the thrust of the spring 46 upon the lever 36 unless the magnet 42 is energized. The lever 35 therefore remains out of the path of the roller 13 and cannot actuate the lever 37 of the contactor. The engagement of the latter is thus prevented in case of failing voltage.

Figure 10 likewise includes particulars of the control circuits in case of utilizing rheostat braking, with the motors short-circuited in the last step of brake application.

In this case, the line circuit-breakers must remain open in rheostat-brake operation: this result is obtained automatically by the suppression of the supply to the lead 116 and therefore also to the lead 153 which supplies the electromagnet 42 (Figures 7 and 10), as soon as the drum or cylinder M of the master switch is pushed over the first brake posi-

tion, which leaves the contacts 109, 105, 110 open.

Upon moving away from zero position, on the brake side, the cylinder M first passes into a position O, in which it supplies a lead 158 by the passage of the segment 155 over the studs 156, 157.

This lead 158 extends to the contacts 159, 160 of the switch CV. These contacts are closed by a segment 161 on the switch CV, if the reversing switch is in the forward position. In this case the brakes can only be applied in forward running.

The lead 158 supplies the magnet SF or 68 (Figures 9 and 10) which when energized brings the brake switch into operation. As soon as this device has rocked it closes the contacts 162, 163 by means of the segment 164 which through the lead 167 connected to 20 the lead 113 supplies the reversing switch backward travel selection magnet V_1 .

As soon as this operation is effected (see Figure 8) the switch CV, closes the contacts 168, 169 at the segment 170, thereby causing 25 the supply of current to the electromagnet RP which controls the longitudinal movement of the shaft g of the combiner.

As soon as the switch CV₁ has turned, its upper segments supplies current to the lead 30 114 and therefore to the lead 116 controlling the magnet EA, if the combiner is at zero position and the contacts 118, 119 are closed.

The magnet EA then actuates the rocking bars K K₁ K₂, first placing the reversing switch in backward travel position and the brake switch in the braking position; at the same time it advances the combiner by one step.

Thereafter the action of the rocking bars 40 engages the contactors for the first step of brake application, as just selected by the combiner.

In the movement of the reversing shaft, the switch CV interrupts the supply to the electromagnets V_1 and SF. But the supply 45 to the lead 158, which would be interrupted at the same time by the contacts 159, 160, is restored by the contacts 171, 172 closed by a segment 173 located on the shaft of the brake switch. This latter therefore remains in place, and the combiner shaft maintains its axial displacement, so long as the lead 158 is supplied by the segment 155 during the 50 brake operation.

After the combiner has advanced one step, the magnet EA is no longer energized.

Advance to the second braking stage by 55 pushing the cylinder M to the position I, supplies current to the lead 180 branched off the lead 151, as well as to the lead 181 branched off the lead 116, by means of studs 184, 185 and 182, 183 and segments 186, 187 respectively.

From the lead 181 there is also taken a

lead 213 which will supply current to the 65 magnet DV and unlock the shaft g of the selector at each change of position, as already described.

It is easily understood that in this way the magnet EA will advance the system by 70 one-step and that the parts remain in place under the action of the contact BP₁ as explained above in the case of overload operation.

The passage to the later braking positions is effected by pushing the cylinder M to the positions II₁, III₁ and so on, allowing the segments 186, 187 to leave their studs so as to interrupt the supply to the electromagnet EA which releases its core and is 80 again actuated by the contact of further segments similar to 186, 187 with the studs 184, 185 and 182, 183.

The last braking step corresponds to the short-circuiting of the motors; this can be 85 produced either by passing through the successive braking steps of the cylinder M or by pushing the cylinder M to the final position by a single movement.

For this purpose, in the last braking position, the segment corresponding to 187 is suppressed and another segment 189 is provided for bridging the studs 190, 191; current is therefore supplied to the lead 192 and through contacts 193, 194, closed by a segment 195 on the shaft of the brake switch when the latter is in the braking position.

The lead 192 supplies the electromagnet FU which causes the hooking of the lever 75 (Figure 9) over one of the teeth on the 100 shaft g of the selector. At the same time it supplies current to the electromagnet EA, through a branch 196, provided that the magnet FU has operated and has closed the contacts 197, 198 by means of its bridge 200. 105

The magnet EA when so energized first sets the selector in the final braking position and then engages the contactors corresponding to this position.

The present electrical control system can 110 evidently be applied to the operation of multiple units; in this case it will be only necessary to connect the leads 139, 116, 141, 113, 112 and 151 to the corresponding leads of the other motor-cars or driving units by intercommunication cables extending along the train or the like.

The invention is likewise applicable to the non-automatic operation of traction circuits; in this case it suffices to determine the intermittent current supply to the lead 116 by 120 suitable known means.

What I claim is:—

1. A control system for electrical equipments, comprising a master switch, an operating device controlled by said master switch, a plurality of contactors, mechanical means 125 for selecting the contactors to be operated,

- and mechanical means for engaging the contactors previously selected, said selecting and engaging means being distinct from one another, but actuated by the same operating device aforesaid.
2. An electric control system, comprising a master switch, a plurality of contactors, means for selecting the contactors to be operated, means for operating said contactors when selected, and means for locking said contactors when operated, said operating means, selecting means and locking means being independent of each other.
3. An electric control system, comprising a master switch, a plurality of contactors, means for selecting the contactors to be operated, means for operating said contactors when selected, means for locking said contactors when operated, and means for locking in non-operated position the contactors not selected, said selecting, operating and locking means being controlled by said master switch.
4. An electric control system, comprising a master switch, a plurality of contactors, means for selecting the contactors to be operated in each position of said master switch, an oscillating shaft, and means carried by said oscillating shaft for operating at each oscillation in one direction the contactors selected for operation, said oscillating shaft being controlled by said master switch.
5. An electric control system, comprising a master switch, a plurality of contactors, means for selecting the contactors to be operated, and means for operating said contactors when selected, said selecting and operating means being controlled by said master switch in successive steps of its movement.
6. An electric control system, comprising a master switch, a plurality of contactors, mechanical means for selecting the contactors to be operated, means for operating said contactors when selected, said master switch controlling said selecting and operating means successively in the several steps of its movement, and positive locking means distinct from said selecting and operating means, said locking means maintaining said contactors in their set positions after each step of said master switch.
7. An electric control system, comprising a master switch, a plurality of contactors, means for selecting the contactors to be operated at each step of said master switch, means for operating said contactors when selected, said selecting and operating means being distinct from one another, and separate actuating means for said selecting and operating means respectively, said selecting, operating and actuating means being controlled by said master switch.
8. An electric control system, comprising a master switch, a plurality of contactors, mechanical means for selecting the contactors to be operated, said selecting means including cams arranged along helical surfaces with means for producing simultaneous rotation and axial travel of said cams, and means for operating said contactors when selected, said selecting and operating means being controlled by said master switch.
9. An electric control system, comprising a master switch, a plurality of contactors, a rotatable cam shaft for selecting the contactors to be operated, levers carrying the movable contact members of said contactors, pivotal supports for said contactor levers, auxiliary levers pivotally mounted on said contactor levers, an oscillating shaft, operating rollers carried by said shaft, said rollers adapted to engage said auxiliary levers and cam-engaging levers operated by said cam shaft to adjust the position of said auxiliary levers.
10. An electric control system, comprising a master switch, a plurality of contactors, a rotatable cam shaft for selecting the contactors to be operated, levers carrying the movable contact members of said contactors, pivotal supports for said contactor levers, auxiliary levers pivotally mounted on said contactor levers, an oscillating shaft, operating rollers carried by said shaft, said rollers adapted to engage said auxiliary levers, cam-engaging levers operated by said cam shaft to adjust the position of said auxiliary levers, locking means carried by said contactor levers for maintaining the contacts in closed position, and means carried by said cam shaft for releasing said locking means upon its return to the off position.
11. An electric control system, comprising a master switch, a plurality of contactors, means for selecting and operating said contactors by successive steps of said master switch, an oscillating shaft included in said operating means, overload circuit breakers for the protection of the system, and means for closing said circuit breakers by the oscillation of said shaft upon initial movement of said master switch.
12. An electric control system, comprising a master switch, a plurality of contactors, means for selecting and operating said contactors by successive steps of said master switch, an oscillating shaft included in said operating means, overload and low-voltage circuit breakers for the protection of the system, means for closing said circuit breakers by the oscillation of said shaft upon initial movement of said master switch, and electromagnetic means for opening said circuit breakers upon fall of voltage.
13. An electric control system, comprising a master switch, a plurality of contactors,

means for selecting the contactors to be operated, means for operating said contactors when selected, said selecting and operating means being controlled by said master switch in successive steps of its movement, and means for obtaining immediate travel of said selecting means to its limiting position in one direction.

14. An electric control system, comprising a master switch, a plurality of contactors, means for selecting the contactors to be operated, means for operating said contactors when selected, said selecting and operating means being controlled by said master switch, means for reversing the motor direction, a brake switch, means for operating said brake switch in successive steps, and means for obtaining immediate travel of said brake switch to its limiting position when

running in the direction governed by said reversing means.

15. An electric control system, comprising a master switch, a plurality of contactors, mechanical means for selecting the contactors to be operated, said selecting means including cams arranged along helical surfaces with means for producing simultaneous rotation and axial travel of said cams, means for operating said contactors where selected, said selecting and operating means being controlled by said master switch in successive steps of its movement, and means for obtaining axial non-rotary travel of said cams at one step in the movement of said master switch.

In testimony whereof I hereunto affix my signature.

PAUL CHARPENTIER.
